UNITED STATES PATENT OFFICE.

JOHN F. KELLY, OF PITTSFIELD, MASSACHUSETTS.

DEVICE FOR PRODUCING ELECTRIC PULSATIONS.

1,134,137.

Specification of Letters Patent.

Patented Apr. 6, 1915.

Application filed September 28, 1912. Serial No. 722,984.

To all whom it may concern:

Be it known that I, JOHN F. KELLY, a citizen of the United States of America, residing at Pittsfield, in the county of Berkshire and 5 State of Massachusetts, have invented new and useful Improvements in Devices for Producing Electric Pulsations, of which the following is a specification.

This invention relates to improvements in 10 devices for producing electric pulsations in which a rotating make and break wheel is employed, the contact sectors of which are placed on a portion only of its surface; and the objects of my improvements are; first, 15 to reduce the cost of construction of such wheels, second, to arrange a suitable number of brushes to coöperate with the comparatively short train of contact sectors so as to furnish the desired number of pulsations per revolution.

This invention is designed for opening and closing an electric circuit for the purpose of producing and transmitting electrical impulses to electro-magnets which are 20 used to operate or set a string or plate in vibration. It is well-known that the natural rate of vibration of a musical string or wire is not, in every instance, a whole number of times per second. It is, therefore, 25 necessary in providing electro-magnetic means for vibrating the wire to energize the magnet as many times per second as the wire vibrates, but, as stated, since the wire does not vibrate a whole number of times per 30 second, the energization of the magnet must correspond as nearly as possible thereto. The present invention has, therefore, as one of its objects to open and close the circuit to the operating magnets as many times as the 35 wire or string vibrates. In accordance with this principle relating to the vibration of a wire, it, therefore, becomes necessary to arrange the contacts and insulation spaces on the rotating wheel distances apart and according to number so as to open and close 40 the circuit as nearly as possible the same number of times as the wire or plate vibrates, regard being had to the fractional parts of a vibration in a given interval of time; usually a second is the period employed in measuring the rate of vibration 45 of a wire or plate.

Referring to the drawings forming a part of the specification,—Figure 1 is a diagrammatic view of the improvement showing a 55 make and break wheel embodying the invention. It is shown associated with means to vibrate a sonorous member if desired. Fig. 2 is a sectional view of the wheel, taken on a plane passing through the axis of the shaft. 60

Referring to the drawings in detail *a* designates the wheel as a whole which is suitably secured to a shaft *b*.

c designates contact sectors that are located on the periphery and electrically connected with each other by the web-portion of the wheel. The contacts *c*, as shown, are in electric contact with the metal body portion of the wheel which is secured to the shaft *b*. These contacts are located on only 70 a comparatively small portion of the circumference as shown, the distance between two of the contacts may be an aliquot part of 360° . *c'* designates the ring of insulation in which the contacts *c* are embedded. 75

d designates brushes suitably arranged at equal angles with relation to each other so as to transmit the electric impulses to the operating magnets in substantially a regular manner depending, of course, upon the 80 spaced relation of the contacts.

In order to illustrate an application of the present invention it is shown associated with a sonorous body *e*, which may represent a wire or plate, a source of current is designated at *f* from one terminal of which a wire *g* leads to an electro-magnet *h*, from its opposite terminal a wire *i* is connected to the brushes *d* by means of a wire *j*. From the other terminal of the magnet *h* a wire *k* connects to a brush *m* that engages the shaft *b*. From this construction it is clear that when the make and break wheel is rotated that electrical impulses or pulsations will be produced and transmitted to the electro-magnet *h* in substantially a regular manner. By placing contacts on a portion only of the wheel and increasing the number of brushes the same number of impulses or pulsations will be produced and transmitted as placing the contacts all around its surface and using only a single brush. As shown there are three brushes employed and contacts placed on practically one-third of the circumfer- 95 100

ence. Where a high rate of impulses is desired it is clear that it is cheaper to increase the number of brushes and lessen the number of contacts than to increase the number 5 of contacts and use only a single brush as heretofore. When the wheel is employed to cause the vibration of a string or plate the contact sectors are made short to produce a quick pull or plucking action on the wire *e* 10 when the electro-magnet *h* is energized, similar to plucking a violin string by hand. It is, of course, not necessary that the angular distance between any two of the contacts is an aliquot part of 360° as the invention is 15 not limited to any such construction. It is necessary, however, that the angular distance between any two contacts shall be the same.

It is to be understood that the space covered 20 by the group of contacts may not be an aliquot part of the circle as, for example, the space occupied by the group of contacts might occupy $3/16$, $3/17$, or $4/17$ of the circumference in which case the impulses 25 would not be an aliquot number because the angle of distance between the brushes is not equal. It is, of course, obvious that the space not occupied by the regular train of contacts and insulating spaces is at least as 30 wide as the pitch.

What I claim, is:—

1. In a rotary make and break device to open and close an electrical circuit to produce and transmit a succession of electrical 35 impulses, a plurality of conducting contacts arranged in a single group on a portion only of the peripheral surface of the make and break device, a source of electrical energy, a plurality of brushes connected in parallel to 40 one terminal of the source of electrical energy, and connections from the other terminal of the source of electrical energy to the other terminals of the brushes to engage the contacts and spaced from each other to produce 45 a succession of impulses, the remainder of the peripheral surface being composed of insulating material, as described.

2. A rotary electric circuit controlling device, comprising in combination, a plurality 50 of conducting contacts distributed in a single group on the periphery thereof, means to electrically connect one terminal of each of the contacts with each other, a plurality of brushes equally spaced from each other to 55 engage the contacts in succession, said brushes being electrically connected together and spaced from each other to cooperate with the other terminal of each of the contacts to produce electrical impulses of equal 60 duration of interval per revolution of the controlling device, and means to insulate the other terminal of each of the contacts from each other.

3. In a device of the character described

comprising a single rotor member, contact 65 elements on said member and distributed over one arc only of its peripheral surface; the remainder of the arc being composed of insulating material, brushes equally spaced from each other to engage the peripheral 70 surface of the contact elements and the insulating material to continuously transmit a succession of single impulses which follow each other at regular intervals, a source of electricity and connections therefrom to the 75 rotor member and brushes.

4. A device for producing and transmitting electrical impulses in combination, a rotor-member, the periphery of which is provided with insulating material, contacts 80 embedded in said material and distributed over an arc of the periphery, a source of electrical energy, brushes connected to one terminal thereof in parallel arrangement and engaging the contacts and connections 85 from the other terminal of the source of electrical energy and to the contacts as described.

5. In a circular rotary make and break device for opening and closing an electrical 90 circuit at substantially regular intervals, a rotating member having a periphery of insulating material, a plurality of conducting contacts spaced equidistantly from each other and arranged in a group covering part 95 only of the peripheral surface of the rotating member, a source of electrical energy, a plurality of brushes spaced equidistantly apart around the periphery of the rotary member and connected in parallel to one 100 terminal of the source of energy, connections from the other terminal of said source to the contacts whereby the current will be interrupted in succession through each of said brushes upon rotation of said rotary 105 member.

6. In a circular rotary make and break device for opening and closing an electric circuit at substantially regular intervals, a rotating member having its periphery formed 110 of insulating material, a plurality of conducting contacts spaced equidistant from each other and arranged in a group which covers a part only of the peripheral surface of the rotary member, the portion of the periphery not covered by the group of contacts being at least as wide as the pitch, a source of electrical energy, a plurality of 115 conducting brushes for engaging the peripheral surface of the rotary member and spaced equidistantly apart around the said surface of the rotary member and connected in parallel to one terminal of the source of energy, connections from the other terminal of said source to the contacts whereby the current will be interrupted in succession through each of said brushes upon rotation 120 of said rotary members.

7. A device for producing electrical pulsations, comprising a rotor member, the periphery of which is divided into insulating and conducting segments, the segments being distributed over an arc of the periphery, and the length of the conducting segments being narrower than the adjacent insulating

segments in order to produce a plucking or picking action.
